US0D1046862S

(12) **United States Design Patent** (10) Patent No.: **US D1,046,862 S**
(45) Date of Patent: ** Oct. 15, 2024

(54) **USER RECOGNITION DEVICE**

- (71) Applicant: **Amazon Technologies, Inc.**, Seattle, WA (US)
- (72) Inventors: **Matthew Christopher Smith**, Seattle, WA (US); **Howie Ho Wai Lau**, Seattle, WA (US); **Jennifer Li**, Seattle, WA (US); **Oluseyi Oluyemisi Babatola**, Seattle, WA (US); **Spencer Ralph Dodge**, Covington, WA (US)
- (73) Assignee: **Amazon Technologies, Inc.**, Seattle, WA (US)
- (**) Term: **15 Years**
- (21) Appl. No.: **29/921,843**
- (22) Filed: **Dec. 19, 2023**

Related U.S. Application Data

- (60) Continuation of application No. 29/875,745, filed on May 9, 2023, now Pat. No. Des. 1,016,812, which is a division of application No. 29/785,329, filed on May 25, 2021, now Pat. No. Des. 991,932.

CLAIM

The ornamental design for a user recognition device, as shown and described.

DESCRIPTION

FIG. 1 is a top, front, right-side perspective view of a user recognition device;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the user recognition device that form no part of the claimed design.

1 Claim, 8 Drawing Sheets
